UNITED STATES PATENT OFFICE.

ARTHUR M. HARBISON, OF BOGGSVILLE, PENNSYLVANIA, ASSIGNOR OF ONE-HALF
TO GUY BUNDY, OF WEST WINFIELD, PENNSYLVANIA.

AUTOMATIC CHOKE-VALVE CONTROL FOR GAS ENGINES.

Application filed August 26, 1926. Serial No. 131,720.

This invention relates to improvements in automatic chokes for the carburetors of internal combustion engines and has as its general object to provide means for automatically controlling the choke valve to regulate the supply of air to the carburetor automatically in consonance with the operation of the engine.

Another object of the invention is to provide an automatic choke so constructed as to obviate the necessity of manually adjusting the choke valve to substantially closed position at the time of starting the engine in cold weather, and which means will operate automatically to open the choke valve to the proper extent as soon as the engine starts, so that no attention of the driver to the adjustment of the choke valve is required.

Another object of the invention is to provide an automatic choke which will depend for its automatic functioning on the partial vacuum or negative pressure in the intake manifold of the engine, so that the choke valve will be automatically adjusted in accordance with the requirements of the engine under different running conditions.

Another object of the invention is to provide an automatic choke mechanism which may be readily installed upon the intake manifold and readily connected to the choke lever of the carburetor.

In the accompanying drawings:

Figure 1 is a side elevation of the automatic choke embodying the invention installed upon the intake manifold and carburetor of an internal combustion engine.

Figure 2 is a detail horizontal sectional view through the mechanism.

Figure 3 is a vertical longitudinal sectional view in detail through the mechanism.

Figure 4 is a view in elevation looking at one end of the mechanism.

Figure 5 is a similar view looking at the other end of the mechanism.

Figure 6 is a detail sectional view illustrating a part of the mechanism.

In the drawings, the numeral 1 indicates the intake manifold, the numeral 2 the carburetor, the numeral 3 the usual shaft upon which the choke valve is mounted, and the numeral 4 the arm which is ordinarily fixed upon this shaft. All of this structure is, of course, old and constitutes no part of the present invention, the only change in the construction being that the usual spring which

is connected with the arm 4 and which normally holds the shaft 3 in position with the choke valve open, is omitted.

The mechanism includes a small cylinder 5 closed at one end by a head 6 and at its other end by a head 7 and the head 6 has a branch which extends upwardly and accommodates one end of an elbow 8, the other end of which elbow is threaded into an opening formed in the wall of the intake manifold, so that communication is established between the intake manifold and one end of the cylinder 5. A piston 9 comprising a head 10 and a stem 11 is slidably mounted in the cylinder 5 and the stem of the piston works slidably through an opening 12 formed in the head 6, a stuffing box 13 being likewise arranged in the outer end of the opening so as to provide a substantially air-tight packing about the stem. A spring 14 is arranged upon the stem of the piston and bears at one end against the inner end of the head 6 of the cylinder and at its other end against the head of the piston, and this spring normally holds the piston in substantially the position shown in Figure 2 of the drawings, or, in other words, in a position with its head 10 at that end of the cylinder to which the head 7 is fitted. The movement of the piston 9 under the influence of the spring is limited by the engagement of the head 15 upon the outer end of the piston stem with the end of the stuffing box 13, and in order that there will be no suction or compression resistance to movement of the piston, vent openings 16 are preferably provided in the head 7 of the cylinder. The numeral 17 indicates a short arm which is secured to the upper end of the choke valve arm 4 and is provided with a series of openings 18 into which one end of a threaded stud 19 may be interchangeably fitted, and a sleeve 20 is threaded onto this stud and is provided with an opening 21 extending diametrically thereof and accommodating one end of a rod or wire 22, the other end of which is connected, as at 23, to an eye provided upon the outer side of the head 15 of the piston stem 11. A set screw 24 is threaded into the sleeve 20 and is adapted to be tightened to bind the said rod 22 so that the desired adjustment may be maintained. At this point it will be evident that when the engine is idle, the spring 14 will hold the piston 9 in the position shown in Figure 2 and in this position the arm 4

will be so inclined as to hold the choke valve open. It will likewise be evident that when the starter for the engine is operated, or the engine is cranked, the suction created in the intake manifold will result in a partial vacuum being created in the cylinder 5 with the result that the piston 10 will be moved longitudinally in the cylinder against the tension of the said spring 14 so as to actuate the arm 4 and move the valve toward an opened position.

As the engine picks up speed, the suction created in the intake manifold will be increased and the piston 10 will be moved to a fully or substantially fully opened position. Of course, when the engine is running and at a relatively low speed, and one, for example wishes to pick up quickly on the road, the acceleration of the engine will result in temporarily reducing the vacuum in the manifold and the spring 14 will move the piston to turn the choke valve, in a closing direction, thus supplying a comparatively rich mixture to the engine and effecting acceleration thereof until normal running conditions are resumed, whereupon the proper vacuum will be again established and the piston will be again moved to adjust the valve to a full open or substantially full open position.

In order to prevent too quick or too early movement of the piston under the influence of the vacuum to open the choke valve, means is provided which will now be described. The said means comprises a cylinder 25 which is mounted preferably upon the head 6 of the cylinder 5 and is placed in communication with the interior of the cylinder 5 by way of a port 26 formed at the juncture of the said cylinder 25 and the head 6, the head 6 at the point where the cylinder 25 is located thereon being hollow and this likewise being the point or portion where the elbow 8 is connected. A piston 27 is arranged within the cylinder 25 and comprises a head 28 and a stem 29 which latter works through an opening 30 in a head 31 fitted onto the lower end of the said cylinder 25 and having vent openings 32 formed therein. A bracket arm 33 is mounted upon the forward side of the cylinder 25 and a lever arm 34 is pivoted, as at 35, to the bracket arm and has pin and slot connection, as at 36, with the lower end of the piston stem 29. The lever arm 34 extends beneath the lower end of the cylinder 25 and thence upwardly in rear of the said cylinder, and is provided with a rearwardly extending finger 37, the upper side of which is provided with a series of rack teeth indicated by the numeral 38, which teeth are to frictionally coact with the periphery of the head 15 upon the piston stem 11. At this point it will be evident that reciprocation of the piston 27 in the cylinder 25 will result in up

and down swinging movement of the arm or finger 37 and a consequent raising and lowering of the finger 37 into and out of position to coact with the head 15. The piston 27, due to the provision of the vent openings 32, assumes by gravity a lowered position when the engine is idle or under conditions where there is but little suction in the cylinder 5, and at such time the detent finger 37 is in lowered position and its teeth 75 are out of engagement with the periphery of the head 15.

At this point it will be understood that when the motor is first started the suction first moves the piston upwardly so that the latch strip engages the disk 15 and retards movement of the piston 10 until the suction has increased sufficiently to overcome the action of the latch and spring. Therefore, the choke valve will not be opened until 85 after a priming charge has been drawn into the cylinders and the motor begins to fire. If the motor begins to labor, as when going up a hill, the suction will be reduced sufficiently to allow the spring 14 to move 90 the piston 10 towards the head 7 and the choke valve will be moved towards a closed position, thereby causing a richer mixture to be fed to the cylinders until the speed of the motor and suction created are again normal. When the motor is stopped, the eliminated suction and back pressure result in the latch returning to an inoperative position and the spring 14 moving the piston 95 to close the choke valve.

In order to provide auxiliary means to control movement of the piston rod 11, there has been provided means which will now be described.

The numeral 39 indicates a resilient bracket member having one end formed with a longitudinally extending slot 40 through which is secured a screw 41 threaded into the outer side of the head 6 of the cylinder 5. One of the spaced portions thus provided is turned outwardly at right angles to provide an ear 42 which supports a finger 43 having a series of teeth 44 formed along one of its edges. A spring 45 is connected at one end selectively with the teeth 44 and at its other end to a U-shaped detent 46 which is slidably mounted upon the outer or rear portion of a rearward extension 47 of the said arm 39, this extension being arcuate and, toward its rear end, being curved in a direction away from the path of movement of the head 15, as best shown in Figure 2 of the drawings. The detent 46 is disposed to straddle the convex side of the extension 47 and a pin 48 is fitted through the side members of the yoke and rides against the concave side of said extension 47, and, in one position of the yoke, coacts with an abutment stud 49 which is carried by the extension 47 and projects from the concave side 120 125 130

thereof. The spring 45 is connected at one rear corner of the yoke and when the pin 48 is in engagement with the stud 49, as shown most clearly in Figure 6, the pull exerted by the spring will cant the yoke so that the rear edge of its connecting portion will engage the convex side of the extension 47 and in this position of the yoke the forward side of its connecting portion will be 10 in the path of movement of the head 15 upon the piston stem 11. Where it is desired to supply a relatively large volume of rich gas to the engine, the throttle is adjusted to half-way open position and the engine is turned 15 over by the starter or by cranking and at this time the partial vacuum created in the cylinder 5 will tend to effect movement of the piston 9 against the tension of the spring 14, but the engagement of the head 15 with 20 the detent 46 will result in a retarded movement of the piston due to the additional resistance offered by the spring 45. At this time, the detent 46 will be moved along the extension 47 of the bracket arm until, due to 25 the curvature of said extension, the head 15 rides past the detent. Where it is desired to supply only a relatively small volume of rich gas to the intake manifold of the engine, the throttle is opened to only a slight 30 degree and the engine is turned over by the starter or by cranking.

Having thus described the invention, what I claim is:

1. In combination with an intake manifold for internal combustion engines and a carbureter connected therewith and having a choke valve and actuating lever therefor, a choke valve control comprising a cylinder having an outlet neck connecting it with the intake manifold of the engine, a piston working in the cylinder and influenced by suction created in the intake manifold to move in a direction to open the choke valve, means yieldably resisting such movement of the piston, a second cylinder in communication with the first mentioned cylinder, a piston in the second mentioned cylinder, a stem for each piston, a latch arm pivotally connected with the second cylinder and connected with the stem of the last mentioned piston, a disc upon the stem of the first mentioned piston, and a detent finger carried by the said arm and having a series of rack 35 teeth thereon for frictional coaction with the periphery of the disc upon the stem of the said first mentioned piston.
2. In combination with an intake manifold for internal combustion engines and a carbureter connected therewith and having a choke valve and an actuating lever therefor, a choke valve control comprising a cylinder having an outlet neck connecting it with the intake manifold of the engine, a piston working in the cylinder and influenced by suction created in the intake manifold to move in a direction to open the choke valve, means yieldably resisting such movement, a bracket member mounted upon the cylinder 40 a longitudinally curved finger extending from the bracket member, a yoke straddling the said finger and movable thereon and constituting a detent, a head upon the stem of the piston for coaction with the said detent, and a spring connected with the detent and with the bracket member and normally holding the detent in position for engagement by the head upon outward movement of the piston.
3. In combination with an intake manifold for internal combustion engines and a carbureter connected therewith and having a choke valve and an actuating lever therefor, a choke valve control comprising a cylinder having an outlet neck connecting it in communication with the intake manifold of the engine, a piston working in the cylinder and influenced by suction created in the intake manifold to move in a direction to open the choke valve, means yieldably resisting such movement, a bracket member mounted upon the cylinder, a longitudinally curved finger extending from the bracket member, a yoke straddling the said finger and movable thereon and constituting a detent, a head upon the stem of the piston for coaction with the said detent, a spring connected with the detent and with the bracket member and normally holding the detent in position for engagement by the head upon outward movement of the piston, and an abutment upon the said finger engageable by part of the detent for limiting the movement of the detent to such position under the influence of the spring.

In testimony whereof I affix my signature.

ARTHUR M. HARBISON. [L. s.]
